ALFRED SHEDLOCK AND WILLIAM SHEDLOCK, OF NEW YORK, N. Y.

Letters Patent No. 74,772, dated February 25, 1868.

MECHANICAL DONKEY.

The Schedule referred to in these Letters Patent and making part of the same.

TO ALL WHOM IT MAY CONCERN:

Be it known that we, ALFRED SHEDLOCK and WILLIAM SHEDLOCK, of the city, county, and State of New York, have invented certain new and useful improvements in mechanism, which we have designated or named the "Mechanical Donkey;" and we do hereby declare that the following is a full description of the same.

The nature of our invention consists, first, in combining, with the series of cog-wheels for giving locomotion to the donkey, a cam-wheel and reacting spring, for the purpose of throwing off or unseating the rider on the back of the donkey at the end of each revolution of the cam-wheel; second, in the combination of an independent and adjustable rider with the reacting spring, for the purpose of unseating him from the back of the donkey; third, in combining, with the feet of the donkey, shoes, having claw-teeth on them, for the purpose of engaging into the surface of the carpet or floor, to prevent any back slip of the feet.

But, to describe our invention more particularly, we will refer to the accompanying drawings, forming a part of this specification, the same letters of reference, wherever they occur, referring to like parts.

Figure 1 is a side view of the donkey and rider.

Figure 2 is a detached side view of the mechanism and legs of the donkey.

Figure 3 is a plan view of the same.

Figure 4 is a detached side view of the cam-wheel and reacting spring for unseating the rider.

Figure 5 is a detached view of the claw-teethed shoes.

Figure 6 is a cut sectional view of the cam-wheel and spring, through the line *x x*, fig. 4.

Letter A represents the frame of the working parts of the apparatus, in which are arranged, on suitable arbors B and C, cog-wheels D and E, and a main-spring, F, for the purpose of giving motion to the series of cog-wheels. On the opposite ends of the arbor B are secured cranks, G, to the centre-pins of which are attached connecting-rods, H, for the purpose of operating the fore and hind legs I and J of the donkey. For the purpose of making the fore and hind legs gather forward alternately, the cranks are set in opposite directions from each other. Therefore, when the fore legs are set on the floor, the hind legs will gather forward, and the reverse will be the case when the hind legs are set on the floor. Also in the arbor B is a loose cog-wheel, K, which is rotated by a pinion-wheel, *e*², on the arbor *c*. On the side or face of the wheel K is a band or rim of metal, L, having a small open space, *f*², between its ends. The object of this wheel and cam-like attachment to its face is to detain or hold down a spring, M, by means of a notched detent-plate, N, attached to the end thereof, and engaging into the band L. By this means, the spring is kept down till the open space *f*² in the band comes round to liberate it, when it immediately reacts, and, by means of the pin P, tumbles the rider Q from his seat on the back of the donkey R. To readjust the spring, it must be depressed, so as to cause the detent-plate N to enter the open space *f*² in the band, and held down until the main-spring F is wound up. It may then be released by the hand, as the band will hold the spring M from reacting until the open space in the band comes round.

It will be obvious that the precise arrangement of the spring, and cam for operating the same, may be modified in several ways. We therefore do not intend to restrict ourselves to the precise arrangement herein described, so long as we accomplish the object of unseating the rider by means of a reacting spring.

For the purpose of preventing the feet of the donkey from slipping backwards on the floor, the feet are armed with metal plates, S, having claw-teeth in their back edges. By this means the feet of the donkey can maintain a secure foot-hold on the floor, and thus keep up a sort of walking motion till the main-spring has exhausted its power.

Having now described our invention, we will proceed to set forth what we claim and desire to secure by Letters Patent of the United States.

1. We claim the combination of the cam-wheel K, made as described, with the spring M, having a notched detent-plate, N, attached thereto, for the purposes hereinbefore described.
2. We also claim, in combination with the reacting spring M and a walking donkey, the independent or adjustable rider Q, for the purposes hereinbefore set forth.
3. We also claim, in combination with the feet of a walking donkey, the claw-teethed shoes S, or equivalent devices therefor, for the purposes hereinbefore set forth.
